CLAIM

The ornamental design for a putter grip as shown and described.

DESCRIPTION

FIG. 1 is a top front side perspective view of a putter grip showing my new design;

FIG. 2 is a front view of the putter grip;

FIG. 3 is a rear view of the putter grip;

FIG. 4 is a left side view of the putter grip;

FIG. 5 is a right side view of the putter grip;

FIG. 6 is a top view of the putter grip;

FIG. 7 is a bottom view of the putter grip;

FIG. 8 is a cross-sectional view of the putter grip taken along line 8-8 of FIG. 6; and,

FIG. 9 is an enlarged view of area 9 of FIG. 8.

The dash-dash broken lines show portions of the putter grip that form no part of the claimed design. The dash-dot broken lines in FIGS. 8 and 9 depict the bounds of the enlarged view and form no part of the claimed design.
